UNITED STATES PATENT OFFICE.

JOHN LUTZ, OF PHILADELPHIA, PENNSYLVANIA, ASSIGNOR TO S. W. EVANS & SON, OF PHILADELPHIA, PENNSYLVANIA, A FIRM COMPOSED OF SAMUEL W. EVANS, WAYNE S. EVANS, AND MORTON E. EVANS.

UMBRELLA GEAT.

Application filed February 12, 1924. Serial No. 692,207.

To all whom it may concern:

Be it known that I, JOHN LUTZ, a citizen of the United States, residing in the city and county of Philadelphia, State of Pennsylvania, have invented a new and useful Umbrella Geat, of which the following is a specification.

My invention relates to a novel construction of an umbrella geat and consists of a plurality of **U** or yoke shaped members which are pivotally mounted on the butt of the stretcher of the umbrella and adapted to be positioned and secured in the rib thereof, said members projecting from their bearings on the stretcher in opposite directions therefrom, so as to provide a lengthened seat for applying the stretcher to the rib, and being held in position by a clip which embraces the rib and yoke members and clamps the latter to the rib, thus connecting the stretcher to the rib in a firm and durable manner, preventing it from being wrenching laterally from the rib, the piercing of the rib for a pivot pin as heretofore practiced being obviated and the invention being also applicable to a parasol.

For the purpose of illustrating my invention, I have shown in the accompanying drawings, forms thereof which are at present preferred by me, since the same will give in practice satisfactory and reliable results, although it is to be understood that the various instrumentalities of which my invention consists may be variously arranged and organized and that my invention is not limited to the precise arrangement and organization of these instrumentalities as herein shown and described.

Figure 1 represents a perspective view of a portion of an umbrella geat embodying my invention.

Figure 2 represents a plan view of the same including a part of a rib to which it is applied.

Figure 3 represents a plan view of the geat in complete condition.

Figure 4 represents a horizontal section of the members shown in Figure 2.

Figure 5 represents a transverse section on line 5—5 Figure 3.

Figure 6 represents a perspective view of a detached portion.

Similar numerals of reference indicate corresponding parts in the figures.

Referring to the drawings:—

1 designates a portion of the rib of an umbrella, and 2 designates a portion of the stretcher thereof, the end portion of the latter being compressed forming the flattened neck or butt 3, as well known in the art.

On the outer end of said butt 3 are mounted the plurality of **U** shaped members 4, each of which consists of the legs 5 and the crowns 6, the latter freely occupying the transverse opening or eyes 7 in said butt, it being noticed that the walls of said eyes form a common bearing for said crowns 6 and permit the stretcher to turn on said bearing during the opening and closing of the umbrella, it being noticed that said legs 5 are seated in the channel of the rib and extend parallel with the latter, and are inclosed by the walls of said channel, and in contact therewith.

In order to retain the legs 5 in position and prevent displacement thereof, I employ the clip 8 which consists of a piece of metal or other suitable material, which is bent around the outer bottom and side surfaces of the rib and provided with the inturned terminals or lips 9, which are deflected downwardly as seen in Figure 5, so as to be positioned between the legs 5, and the butt 3, thus tightly holding the parts in assembled position, said lips being separated to permit the butt 3 to oscillate between them in the motions of the stretcher in opening and folding of the umbrella and permitting the stretcher to fold into the rib when the umbrella is closed.

It will be noticed that both the **U** shaped members 4 are held by the clip 8, in the channel of the rib, thus equalizing the connection of the stretcher with the rib on opposite sides of the eyes 7, and the legs 5 form aligning continuities of each other, thus providing a double device and consequent elongated surfaces for connecting the stretcher with the rib, each section of said device being positioned at different places in the length of the rib and obviously preventing all liability of the stretcher being wrenching or twisted out of the rib.

It will be further noticed that the rib 1 is

not pierced and so weakened by openings to receive a pivot pin, and that while such piercing and pin are obviated, the firm and reliable connection of the stretcher with the 5 rib is secured.

The limbs 5 of the yoke 4 are preferably made of material half round in cross section, as will be understood from the right hand end 5 of Figures 1 and 6, and it will be understood that the inturned lips 9 are slotted so as to accommodate the crowns 6 of the yokes 4, when said parts are assembled as seen in Fig. 5, the slots being omitted from Fig. 3, for clearness of illustration. The yokes 4 are duplicates so that the expense of manufacture and assembling is obviously reduced to a minimum. I am aware that it has been heretofore proposed to employ a single U-shaped member, having flattened ends, but my device possesses advantages thereover, since half round wire gives greater strength, and as there is always a possibility of a single joint showing some defect, the assembly of two yokes in the manner described offers a greater margin of safety. Furthermore, the assembly of the prior art requires two operations, whereas the assembly of my present invention requires but a single operation. There is also added strength in my present device, because with the single yoke of the prior art only two ends thereof can be clipped, whereas with the double yoke of my present invention four ends can be clipped, thus producing a very rigid and durable construction.

It will now be apparent that I have devised a novel and useful construction which embodies the features of advantage enumerated as desirable in the statement of the invention and the above description and

while I have in the present instance shown and described the preferred embodiment thereof which has been found in practice to give satisfactory and reliable results, it is 45 to be understood that the same is susceptible of modification in various particulars without departing from the spirit or scope of the invention or sacrificing any of its advantages. 50

Having thus described my invention, what I claim as new and desire to secure by Letters Patent, is:—

1. In an umbrella, a stretcher having an eye through the butt thereof, a plurality of U-shaped yokes composed of semicylindrical legs and crowns, said legs and crowns being of the same width throughout, the convexed portions of said legs being juxtaposed to each other, said yokes being positioned on said butt with their legs extending oppositely to each other in the longitudinal direction of the stretcher, and the crowns of said yokes having a common bearing in said eye. 55

2. In an umbrella, a stretcher having an eye in the butt thereof, a plurality of U-shaped yokes composed of semicylindrical legs and crowns, said legs and said crowns being of the same width throughout, the convexed portions of the said legs being juxtaposed to each other, said yokes being positioned on said butt with their legs projecting oppositely to each other in the longitudinal direction of the stretcher, and the crowns of said yokes having a common bearing in said eye, a rib, and a clip clamped on said rib and having inwardly deflected terminal lips engaging the legs of said yokes to secure the latter in position. 70 75

JOHN LUTZ.
